UNITED STATES PATENT OFFICE.

RALPH H. ANDERSON, OF SPOKANE, WASHINGTON.

FOOTBALL-GAME APPARATUS.

Application filed December 31, 1926. Serial No. 158,304.

The object of this invention is to provide a novel form of foot ball game apparatus whereby the game of foot ball may be played in close simulation to the actual outdoor practice.

One of the features of my apparatus is to provide relatively movable elements, one being a ball guiding and the other a field element on which latter the field is outlined, 10 there being a foot ball simulating member in guided relation to one of said elements and in actuated relation to the other of said elements.

A feature of my invention consists in providing a ball simulating member that is 15 floatingly and indiscriminatively movable, within certain limits, so that as the coacting and relatively movable elements are actuated, the ball member will execute various 20 movements and take various positions on the field wholly at variance with any predetermined order either between or outside the side lines as thereby greatly to enhance the uncertainties and stimulate by the element 25 of surprise to an extent equal to the game as played out of doors.

A further feature consists in a novel form 30 of yardage indicator which is slidably and frictionally associated with the field element in a manner to travel therewith to a predetermined extent, and which is manually adjustable, or capable of being "set" to account 35 for the yardage made.

A further novel feature consists in means 40 for indicating to the players when a period such as a quarter has been completed, said means preferably being of the audible type and being actuated in a novel manner by the same means which adjusts the field element.

In accordance with my invention, the field 45 element is normally held against movement and novel means of a manually operable nature is provided to move the field element in different directions in the course of play, said element always being held strictly to the position to which it has been adjusted.

It is a feature of my invention to subdivide the playing field into a plurality of sections, preferably parallel with the side 50 lines, and to provide a deck of playing cards equipped with play designating data, and also with yardage indicating data, the latter being arranged in accordance with the number of sections into which the field is divided.

My invention has many other features which will be more fully described in connection with the accompanying drawings and which will be more particularly pointed out in and by the appended claims. 60

In the drawings:

Fig. 1, is a plan view in elevation of my improved playing mechanism.

Fig. 2, is a sectional view on line 2—2 of Fig. 1. 65

Fig. 3, is a vertical sectional view on line 3—3 of Fig. 1.

Fig. 4, is a vertical sectional view on line 4—4 of Fig. 3.

Fig. 5, is a vertical sectional view on line 5—5 of Fig. 3. 70

Fig. 6, is an enlarged plan view of the ball simulating element and the guiding means for holding the ball member in actuated relation to a field element. 75

Fig. 7, is a sectional view on line 7—7 of Fig. 6.

Fig. 8, is a sectional view on line 8—8 of Fig. 7.

Fig. 9, is a playing face view of one of my improved cards. 80

Fig. 10, is a similar view of another of the cards.

Like characters of reference designate 85 similar parts throughout the different figures of the drawings.

My invention, as shown, includes a frame which is preferably in the form of a casing, having a bottom 1, end walls 2 and 3, and a casing wall 4, the latter being provided with an observation opening 5. Within the casing is what I will term a field element which is specifically in the form of a cylinder 6, the same being provided with a drag or braking shoulder 7. Said cylinder 6, is shown 90 mounted on a spindle 8, preferably rigidly, and one end of said spindle 8 is journalled at 9, in wall 2, the other end of said spindle being journalled in a bearing 10, forming a part of an upright 11, mounted on a base 12. 100 This base 12 is suitably anchored to bottom 1, and will be further described. It will be seen that wall 4, is semi-cylindrical at the top of the casing and that the cylinder 6, is concentric therewith, with a suitable clearance and so that a peripheral portion of the cylinder 6 may be observed through opening 5.

As will later appear, I desire to provide 110 the periphery of cylinder 6 with a friction

surface and in practice, I cover the same with felt 13, for the reason that cylinder 6, functions as an actuating element. On the exposed surface of the felt is delineated the 5 lines of a foot ball field, the side lines being indicated at 14, and extending circumferentially of the cylinder, and the transverse lines 15, which indicate or divide the yardage, into sections of ten yards. It will be 10 noted that the margins 16, of opening 5, disclose areas of the field laterally of the side lines, which areas are designated at 17. The yardage lines 15 are numbered, as indicated at 18, and the complete field is delineated including goals, which it is not necessary to 15 show.

Foot ball means is disposed in coaxing relation to the field element and will now be described in detail.

20 A guiding element is provided in the form of a ball rod 19 which is shown mounted on end walls 2 and 3, and which extends parallel with the yardage lines 15 and across the field beneath the casing and in relatively 25 close relation to the field. It is a feature of my invention, in order to add to the attractiveness of the game, as will later appear, to divide the playing field into a plurality of sections, and in this form of the 30 invention, this feature is accomplished by coloring rod 19, say yellow, at the center of the field, as indicated at 20, and red, near the sides of the field, as indicated at 21. Of course, these precise colors are not essential, but the purpose is to visually divide the 35 field into sections extending circumferentially thereof.

It is a feature of my invention to provide 40 foot ball simulating means which I will next describe in detail.

I employ a ring 22, which as shown more 45 particularly in Figs. 6 to 8, is not cylindrical in cross section, but is in the form of a ring band which may be of metal or other material. It will be seen that the internal diameter of the band 22, is very greatly in excess of the diameter of rod 19, and the width of the band is such, as regards the distance between rod 19 and the field, that one margin 50 23, will engage the rod 19 while the other margin 24, will engage the felt 13. The parts are so proportioned that the band 22, will always overbalance from the vertical either to one side or the other, while being 55 actuated by the moving felt 13. I make the band 22 of extremely light weight material so that it will be very responsive to the actuation of the felt 13. Now by reason of this construction, the ball simulating element 22 60 will move indiscriminately from one side of the field to the other, sometimes remaining in the center and sometimes even going laterally of the side lines 14 by reason of the floating relation of the band with respect to the rod 65 19. Of course, the band 22 is, as will be seen,

loosely threaded on the rod and hence the variant movement of the band will always be in a linear path because it is guided by rod 19. This is also an advantage because it is desirable to always have the ball member 22, 70 within observation through opening 5. While I have shown the field cylindrical and the rod fixed, it will be clear that the field element and the ball means have relative movement with respect to each other, one of the 75 elements functioning as an actuating element and the other as a guiding element. It will also be clear that as the field is rotated, the band 22, will be rotated around 80 rod 19.

Reference will next be made to the novel manual means for imparting movement to the field.

A bar 25, is mounted to oscillate about spindle 8, and is disposed between bearing 85 10 and the adjacent end of cylinder 6. Said bar 25, overhangs annular shoulder 7, at 26, and there is mounted on end 26, a strip spring 27, the end portions of said spring extending circumferentially over shoulder 90 7, as shown, and having radially inwardly turned cnds 28, preferably sharpened or pointed, for engagement with said shoulder 7. Knobs 29 and 30, are disposed in a position accessible from the exterior of the casing and said knobs have rods 31 and 32, respectively, which extend through a slot 33 in the casing, and are mounted rigidly on said spring 27, as shown. Thus, if a player on the left of Fig. 4, wishes to shift the field, 100 he manually depresses knob 29 until the corresponding end 28, is engaged with shoulder 7, then, by shifting the knob 29, either to the right or left of Fig. 4, he can cause a corresponding movement of cylinder 6, to vary 105 the position of the field with respect to the ball. Just as soon as he releases pressure on the knob, the spring will release tractive engagement between the end 28 and the cylinder. I provide two knobs to afford one for 110 each player, but both knobs are identical in structure and operation, hence, only one need be described. In order to move the cylinder 6, the required extent, it may be necessary to make more than one oscillation of 115 the knob, which will be clear from the foregoing.

In order to prevent the cylinder from being accidentally moved, I provide means which I will next describe.

A drag shoe 34, engages shoulder 7, and has a stem 35 that slides through a boss 36, mounted on upright 11. A spring 37, is interposed between said shoe 34 and said boss 36, and normally engages the shoe against shoulder 7 with a sufficient amount of traction to hold the cylinder against accidental movement and yet permit the cylinder to readily be shifted by the means just described.

It is a feature of my invention to provide means for indicating to the players a period of play, or the completion of a period of play, which, in foot ball, may be a quarter.

5 As shown, the base 12, has an upright 38 having a bearing 39 which is in line with a bearing 40, on upright 11. A counter-spindle 41, is journaled in said bearings 39 and 40 and is mounted on said spindle 41, a 10 toothed wheel or disc 42, having ratchet teeth 43. A pawl 44, actuated by a spring 45, is pivoted at 46, to bar 25, and as the latter is oscillated, rotative movement in one direction only, is imparted to wheel 42. Se- 15 cured to disc 42, or fixed to spindle 41, as desired, is a cam 47 having a tooth 48. A drag spring 49, is mounted on bottom 1, at 50, and the upper end 51, may be slightly forked to engage the marginal edge of cam 20 47, under considerable pressure. The direction of rotation of the cam 47, as well as disc 42, is clockwise, viewing Fig. 4, and therefore as spring 51 is suddenly released by tooth 48 and impacts on the shorter 25 radius of the cam 47, a note of warning is audibly heard that indicates that a period of play has been completed. It will be clear that the spring 51, also acts as a drag, and therefore prevents any idle movement of the 30 disc 42 and cam 47, and securely holding the same as the pawl 44 rides over the teeth 43, to take a new grip. In practice, the teeth 43 will be made small enough to insure accurate movement of the cam 47, upon actuation of the 35 means for shifting the cylinder. It will now be clear that the manual means for shifting the cylinder, operates the period indicating signal mechanism.

40 My invention includes an improved yardage indicator which I will next describe in detail.

The indicator proper, is shown at 52, the same being of a length coincident with ten yards, and being graduated into one yard divisions. Suitable finger grips 53, are provided for adjusting said indicator and the latter is movable in a slot 54, in the casing. Said indicator is mounted on or integral with a supporting arm 55 which extends 50 downwardly and is oscillatable on spindle 8, a spring 56, holding said arm 55 toward the left hand end of cylinder 6. Said arm 55 is provided with a slot 57, through which rod 19 projects, the latter limiting oscillating movement of the indicator and also limiting movement of the indicator with the cylinder 6. Said arm 55 is provided with friction members 58 adapted to engage the left hand end of cylinder 6 so that a sufficient frictional engagement will result to normally cause the indicator to follow the movement of the cylinder. However, the indicator can be manually adjusted independently of the cylinder.

65 In use, the device of my invention is em-

ployed with a pack of cards, one being shown in Fig. 9.

As illustrated, the playing face of said card 59, is divided into four vertical columns 60, 61, 62 and 63. In column 60, I have 70 designated the various names of plays that may be made. Column 61, is the left section of the field, which would be one of the red sections visualized by a red portion 21, of rod 19, dependent upon the direction the 75 player was facing the device shown in Fig. 1. Column 62, is the central section, visualized by the yellow portion 20, of rod 19. Column 63, is the right section, visualized by the remaining red portion 21. In these 80 columns, will be found numerals and legends showing the yardage to which the ball 22 must be moved.

Having described the structure of my invention, I will next briefly describe one manner in which the game of foot ball may be played.

The cards are first shuffled and disposed face down. The player opening the game manually moves the ball 22 to his own forty 90 yard line, and grasping one of the knobs, or rather the knob on his side, say 30, moves the latter back and forth, without depressing the knob to actuate the cylinder, until the tooth 48, of cam 47, releases spring 51. The 95 resulting click, audibly indicates that the game may be started, or rather the first quarter. Although the ball 22 is always placed in the center section on kickoff, the play desired may be selected from any section of the card. Assuming that player A decides to kick off, he will turn over the first card from the deck and select a kickoff. He will then actuate the field until the ball has been moved toward his opponent's goal the 100 105 selected distance designated on the card. If the ball goes out of bounds, the play must be made over again, player A, drawing another card. After the kickoff, the second player B, turns over the next card, and returns the ball the distance designated, in that section of the field corresponding to the section of the field in which the ball is located. The player B, now has the ball, and is now the offensive player. The defensive 110 115 player A, now draws two cards. The offensive player may now call for any play. The object of defensive player A, is to play a card that will give his opponent the least possible gain, or in fact a loss, or if possible, to cause his opponent to fumble the ball or by intercepting a forward pass, and thereby gain possession of the ball.

If the ball is in the left section of the field, that is, to the left of the player facing the device, the plays used are designated on the left section of the card, of such player. If the ball is in the center or right sections, the corresponding sections of the card are used. After the card has been played, the 125 130

offensive player B, causes the ball to be moved forward or backward with respect to the field, as directed on the card.

It will be clear that the device of my invention may be employed in various kinds of plays, and with various methods of play, and it is thought that the foregoing will be illustrative.

It is believed that the invention will be fully understood from the foregoing description, and while I have herein shown and described one specific form of my invention, I do not wish to be limited thereto except for such limitations as the claims may import.

I claim:

1. A foot ball game apparatus comprising, a casing having an observation opening therein, a cylinder rotatively adjustable in said casing with its periphery disposed abreast of said opening, the periphery of said cylinder having delineated thereon the side and transverse lines of a foot ball field with the side lines extending circumferentially of said cylinder, a rod mounted in said casing and extending across said opening and in close relation to the periphery of said cylinder parallel with the transverse lines of the field, and a foot ball simulating ring loosely threaded on said rod and having gravity engagement with the periphery of said cylinder for movement of said ring transversely of said field as said cylinder is rotatively adjusted.

2. A foot ball apparatus comprising, a casing having an observation opening therein, a cylinder rotatively adjustable in said casing with the periphery of said cylinder abreast of said opening, the periphery of said cylinder having delineated thereon the transverse and side lines of a foot ball field with the side lines extending circumferentially of said cylinder, a rod mounted in said casing and extending across said opening parallel with the transverse lines and in close relation to the periphery of said cylinder and said rod being visually sub-divided longitudinally to divide the field into a plurality of separate sections, and a foot ball simulating ring loosely threaded on said rod and engaging the periphery of said cylinder, whereby rotative adjustment of the latter will cause indiscriminate movement of said ring longitudinally of said rod and across said field.

3. A foot ball game apparatus comprising, relatively movable field and rod elements and the field element having delineated thereon the lines of a foot ball field, and a foot ball simulating ring band threaded on said rod element and frictionally engaged by said field element, said elements being in sufficient adjacency and said band being sufficiently enlarged in diameter to overbalance in different directions from the vertical and floatingly move to different positions on said

field element as said elements are relatively actuated.

4. A foot ball game apparatus comprising, relatively movable field and rod elements in close relation and said field element having delineated thereon the lines of a foot ball field, and a foot ball simulating ring band threaded on said rod element and frictionally engaged by said field element, said ring band being sufficiently enlarged in diameter and of sufficient width whereby it will overbalance from the vertical by gravity with an inner margin engaging said rod element and an outer margin engaging said field element.

5. A foot ball game apparatus comprising, guiding and actuating elements relatively movable with respect to each other and one of said elements having the lines of a foot ball field delineated thereon, and a floating and indiscriminately movable foot ball simulating member in guided relation to one of said elements and in actuated relation with the other of said elements.

6. A foot ball game apparatus comprising, guiding, guiding and actuating elements relatively movable and one of said elements having the lines of a foot ball field delineated thereon, one of said elements having means for visually dividing said field into sections, and a foot ball simulating member floatingly associated with one of said elements and actuated by the other of said elements to assume a variety of different positions on the field upon relative movement of said elements.

7. A foot ball game apparatus comprising, a movable element having on its face the lines delineative of a foot ball field, ball simulating means abreast of said field, manual means for moving said element in different directions during the course of play, and mechanism operated by said means for indicating the completion of a period of play.

8. A foot ball game apparatus comprising, a rotatively adjustable cylinder having the lines of a foot ball field peripherally delineated thereon, ball simulating means abreast of said field, means for rotatively adjusting said cylinder in opposite directions in the course of play, and mechanism operated in one direction by said means for audibly indicating the completion of a period of play.

9. A foot ball game apparatus comprising, a frame, a cylinder rotatively adjustable in said frame and having the lines of a foot ball field delineated on its periphery, a foot ball simulating means abreast of said field, means for adjusting said cylinder in different direction in the course of play, and a yardage indicator frictionally associated with said cylinder.

10. A foot ball game apparatus compris-

ing, a frame, a cylinder rotatively adjustable in said frame and having the lines of a foot ball field delineated on the periphery thereof, a foot ball simulating means abreast of said field, means for adjusting said cylinder in different directions during the course of play, a yardage indicator frictionally associated with said cylinder to move therewith, and means for limiting movement of said yardage indicator.

11. A foot ball game apparatus comprising, relatively movable ball and field elements and the field element having lines thereon delineating a foot ball field, one of said elements having means for subdividing the field into a plurality of sections on lines parallel with the side lines of the field, and a pack of cards, each card having yardage columns corresponding

in number to the number of sections into 20 which the field is divided and also a play column bearing the names of various plays, the yardage columns bearing opposite the names of play the number of yards the ball is to be moved in accordance with the play- 25 ing section in which the ball is disposed.

12. A foot ball game apparatus comprising, a pack of cards, each card being divided into a playing column bearing the names of different plays, and each card being divided 30 into "left" "center" and "right" yardage columns, and said yardage columns bearing various numbers and play legends of penalty and advance character.

In witness that I claim the foregoing as 35 my own, I hereby affix my signature.

RALPH H. ANDERSON.
